Primary Examiner — Catherine A Tuttle(74) *Attorney, Agent, or Firm* — Sterne, Kessler, Goldstein & Fox P.L.L.C.(57) **CLAIM**

The ornamental design for a toy musical instrument, as shown and described.

DESCRIPTION

The sole FIGURE is a top front perspective view of the toy musical instrument showing our new design.

The broken lines in the FIGURES show portions of the toy musical instrument that form no part of the claimed design. Portions of the toy musical instrument that are not shown form no part of the claimed design.

1 Claim, 1 Drawing Sheet(56)
